UNITED STATES PATENT OFFICE.

WILLIAM E. RAMSEY, OF CHICAGO, ILLINOIS.

FLOOR CONSTRUCTION.

Application filed March 2, 1923. Serial No. 622,289.

This invention relates to a floor construction which utilizes a plurality of pre-cast plates or slabs, such as would result from the use of concrete properly reinforced, these plates or slabs being extended between suitable supports, as, for example, girders or I-beams which are arranged in parallelism at desired intervals in accordance with usual practice in building.

For its principal objects my invention aims to provide a floor construction which may be produced with a minimum of expense; which will be sufficiently strong to sustain its intended load; which may be easily set up and installed by workmen of average or ordinary skill; which will possess adequate strength without an excess of weight; and a construction from pre-cast materials which may be handled, packed and shipped with the maximum of convenience and safety. In these respects, as well as others which will hereinafter appear, my invention is characterized by certain improvements most of which are set forth in the specification and claims to follow, and in the accompanying drawings which illustrate certain embodiments of my invention in the manner following:

Figure 1 is a view in perspective, partly broken away, to show in section a floor construction which utilizes supports in the form of girders or I-beams of conventional design;

Fig. 2 is a sectional view taken in various planes each of which parallels the girders shown in Fig. 1;

Fig. 3 is a sectional detail taken on line 3-3 of Fig. 2;

Fig. 4 is a sectional detail shown on line 4-4 of Fig. 3;

Fig. 5 which is a view similar to Fig. 3 shows the construction modified for use with a girder of lesser vertical dimension;

Fig. 6 is an enlarged detail showing one form of tying the floor and web plates together;

Fig. 7 is an enlarged detail in section showing a tying connection between the web and ceiling plates;

Fig. 8 is a similar view wherein a lathing to which a plaster coat may be applied, is substituted for the ceiling plates elsewhere shown; and

Fig. 9 is a detail in section illustrating a floor construction wherein the web plates are

arranged vertically instead of obliquely as in the remaining figures.

The present floor construction is adapted to extend between suitable supports such as girders A and B which may be carried upon columns or pilasters in the usual manner. These girders are shown in the form of conventional I-beams each having a web 10 and upper and lower flanges 11 and 12, respectively. The distance that these girders are spaced apart is, of course, determined usually with reference to the strength of the floor components which are extended between them.

According to this invention, use is made of a plurality of plates or slabs, each preferably pre-cast from concrete or other suitable plastic material having the requisite properties and suitably reinforced with the aid of rods or bars. In general, these plates are of three kinds, those designated as C being termed the floor plates, those bearing the letters D as ceiling plates, and the intermediate or oblique plates E being referred to as web plates. These several plates may be produced economically in moulds, and to reduce weight without sacrifice of strength are shown to be provided with recesses 13 in the case of the floor and ceiling plates, and with holes or openings 14 in the web plates. When so formed they are both convenient and suitable for handling and shipping.

A plurality of floor components of the general kind described are arranged so as to extend transversely between the spaced horizontal supports A and B. In assembling the plates, a block F of concrete or other appropriate material is preferably arranged adjacent the girder webs 10 and suitably rested upon a foundation 15 of concrete below which may be positioned a shoe tile G of the usual kind. The block F is shown to be formed with some sort of a shoulder 16 on which may be rested the ends of the several ceiling and web plates so as to provide a support therefor. The web plates and ceiling plates are thereafter assembled after the general manner indicated in Fig. 1, triangular end plates H being preferably arranged between the several web plates, and inverted alternately as indicated in Fig. 4. These end plates lie relatively close to the girder and serve as a retaining wall for a concrete fill 16^a which is poured around the girder in the manner best shown in Fig. 3.

With the exception of the construction of Fig. 9, all of the web plates are arranged obliquely with respect to the floor and ceiling plates. More particularly, the web plates are shown as in right angular relation to each other so as to form angles of 45° on their upper and lower sides, respectively, with the floor and ceiling plates. This arrangement may be modified, however, as suggested in Fig. 9, where the web plates are vertically disposed in right angular relation to the floor and ceiling plates, and in parallelism with each other.

The floor components which are related to each other and to the girders in the general manner described are further arranged to interlock so as to form, in effect, a unitary structure which is practically independent of mortar or any other cementing medium. For this purpose, the edges of the several plates are specially formed with notches so as to provide intervening lugs or teeth which co-operate with like formations on the adjacent plates. In the case of the web and ceiling plates, these lugs or teeth so interengage as to form an interlock. With the floor plates an interlock is also provided which may or may not connect with the interlock at the upper edges of the web plates. Additionally, however, these lugs or teeth in the floor plates are so arranged as to leave at intervals open spaces wherein mortar may be received to provide a supplementary tie between them.

Referring now to Figs. 1 and 2 the edges of the several ceiling plates are shown to be provided with alternately formed notches and lugs, and these may take on four distinct formations which occur successively throughout the length of the several plates or slabs. The cross section of Fig. 2 which is taken in four successive planes sets forth these several formations which may be advantageously employed. One of these shows notches having oppositely disposed oblique edges 17 so as to provide between them a V-shaped pocket, wherein may be received the lugs formed on the proximate edges of two web plates. By the numeral 18 I have indicated lugs which occupy substantially abutting relations, their upper faces being formed with grooves 19 in which may be received lugs which project from the proximate edges of the web plates. Another formation is suggested where the numeral 20 indicates the rear oblique edge of a notch into which is projected a lug 21 from the adjacent ceiling plate, this lug having upper and lower oblique faces 22 and 23, respectively. In the last formation the notch has a rear face 24 that is obliquely inclined, the notch being in co-operating relation with another notch having an oblique face 25 oppositely disposed so as to form, in effect, a V-shaped pocket, wherein may be

received the lugs of one of the proximate web plates.

Assembled with a plurality of ceiling plates which may have the special construction just described, are the several web plates which, according to Figs. 1 and 2, are obliquely disposed so as to lie in right angular or other definite relation to each other. As shown, they are arranged in zig-zag formation between the ceiling and floor plates. These web plates are also notched along their opposite edges so as to interlock with each other as well as with the ceiling and floor plates, the lugs or teeth which intervene between the notches being specially formed for this purpose. According to the showing in Fig. 2, certain of the lugs on the web plate are provided with oblique faces 26 disposed in substantially vertical planes when the webs are set up. These lugs which lie adjacent the edges 17 forming notches on the ceiling plates, are adapted to occupy the spaces therein, but not to extend beyond the lower face thereof. Other of the web plate notches, designated by the numeral 27, are formed to lie within the grooves 19 so as to find a bearing therein. The numeral 28 indicates other lugs on the web plates which are formed to rest upon the upper face of the ceiling plates, but spaced from each other for a purpose which will presently appear. At 29 the lugs are shaped to enter into the V-shaped spaces between the notches on the ceiling plates, the adjacent lugs 30 on the next web bearing against the lug 29, as shown.

Along the edges of the web plates which lie remote from the ceiling plates, that is, adjacent the floor plates on their under sides, lugs having a different formation are provided. The numeral 32 designates one lug having a curved top surface with which co-operates other lugs 33 from the adjacent web plate. The lug 34 is provided with an oblique bearing face adapted to rest squarely against the under side of the floor plates. Another lug 36 presents one edge to a like lug on the adjacent plate so as to provide V-shaped troughs or pockets at intervals along the upper edge of the web plates.

The floor plates whose construction appears best in Fig. 2 have also suitable lugs arranged successively along their adjoining edges, these being denominated by the numeral 37. At intervals a lug is missing so as lugs 36 of the web plates so as to provide a lateral border for the pockets which are substantially enclosed except upon their upper sides. In addition to these several plates which are so formed as to co-operate with each other in the manner described, it should be noted that the end plates H which are of triangular shape occupy positions adjacent the ends of the ceiling plates and the

web plates, the latter of which have inclined ends 39, as suggested in Fig. 3, so that their general shape is that of a trapezoid. The extremities of these web plates may also be 5 rested upon the blocks F, as well as upon the ceiling plates, or, in fact, be supported with entire independence of the ceiling plates, if desired.

The various lug and notch formations 10 which have been suggested may, of course, be variously modified. According to the forms suggested, I provide suitable bearings in which the lower edges of the web plates are received, thus preventing any downward 15 movement or horizontal displacement. In addition, the web plates provide between them vertical faces, opposing each other, thereby affording a solid vertical bearing for any horizontal force. The ceiling plates 20 are further beveled to fit below the web plates so as to resist any upward movement of the former. These various notched formations further provide means for holding the web plates in position upon the ceiling plates prior to being cemented with mortar. Such details of construction, however, may be worked out to suit individual requirements and are not to be considered as of 25 primary importance to this invention.

The mechanical connection which I have suggested for the ceiling, web, and floor plates may be further supplemented by ties such as the following: Extending from suitable reinforcements 40 such as would ordinarily be employed in the construction of 30 these plates, are wires 41 which project from the notched edges so as to lie within the pockets 38, as indicated in Fig. 6, or elsewhere, according to the particular location. The ends of these wires which may be 35 bent in any suitable fashion are embedded in a little fill of concrete or other cementitious material which is introduced into the pockets. In addition, a shallow fill of concrete 45 42 may be arranged between the several web plates along the troughs formed by their meeting edges. If wires connecting with the reinforcements be protruded from these plates along their edges, the same may 50 be buried within the concrete fill thus introduced so as to further tie the plates together.

The concrete fill which is arranged around the girders should be carried up approximately 55 to the level of the floor plates, as indicated in Figs. 1 and 3 so as to provide a floor construction whereon may be added a fill of cinders or the like for supporting the boards or other surfacing material.

The construction suggested in Fig. 5 60 makes use of floor components the same as those elsewhere described. The ceiling plates in this case, however, are supported in a plane which is just below the lower web 65 of the girder so as to provide a ceiling con-

struction which is of uniform height. In all other respects the construction follows that which has been elsewhere described.

By the construction of a floor in accordance with the preceding description, I am able to produce both upper and lower surfaces which are practically level and unbroken. The strength of such a floor is substantially proportional to its thickness but in accordance with the present construction, this strength is obtained with a minimum of floor weight owing to the open spaces which intervene between the ceiling web and floor plates. Preferably the shape of the several plates is such that their major 70 surfaces are flat and smooth so as to assist in piling in compact form whether for storage or transportation purposes.

I claim:

1. In a floor construction having spaced 85 supports, the combination of a plurality of plates extending in edge to edge relation from one support to another, each plate having one end rested upon the proximate support, other plates arranged in edge to edge 90 relation above the first named plates, and a plurality of web plates disposed obliquely and intermediately of the other sets of plates, the web plates being interlocked to each other and to the various plates to which they 95 are proximate, substantially as described.

2. In a floor construction, the combination 100 of ceiling plates, floor plates arranged thereabove in spaced relation, web plates intermediately of the ceiling and floor plates, means for interlocking the ceiling plates with each other and with the web plates, means for interlocking the web plates to each other and to the floor plates, and suitable supports on which the ceiling plates 105 are rested, substantially as described.

3. In a floor construction, the combination 110 of a plurality of interlocking ceiling plates above which in spaced relation are a plurality of interlocking floor plates and intermediately of the ceiling and floor plates a plurality of interlocking web plates adapted also to interlock with the floor and ceiling plates, and means whereon the ceiling plates are rested to provide a support for the floor, 115 substantially as described.

4. In a floor construction, the combination 120 with suitable supports of a plurality of pre-cast plates formed from concrete or the like, the several plates being variously formed and assembled to provide a plurality of ceiling plates arranged edge to edge with a portion of each rested upon the supports, a plurality of web plates upstanding from the ceiling plates, a plurality of floor plates 125 arranged edge to edge and rested upon the upper edges of the web plates, and inter-engaging means at the edges of the several plates whereby they are connectable to each other, substantially as described.

5. In a floor construction, the combination of a plurality of ceiling plates arranged edge to edge above which in spaced relation are a plurality of floor plates arranged edge to edge and intermediately of the ceiling and floor plates a plurality of web plates adapted to transmit support from one to the other, other plates arranged vertically adjacent the ends of the web plates adapted to close the spaces therebetween, supports on which the ends of the ceiling plates are rested, and means filling the space between each support and the end plates adjacent thereto, substantially as described.
6. In a floor construction, the combination with a pair of I-beams, of a shoe tile secured to the lower web of each, a concrete foundation superimposed on the shoe tile, a shouldered block resting on the foundation, a plurality of ceiling plates extending between the I-beams with the ends of each resting upon the block shoulder to derive support therefrom, a plurality of web plates upstanding from the ceiling plates, a plurality of floor plates resting upon the web plates, plates arranged adjacent the ends of the several plates adapted to close the spaces extending transversely between the I-beams, and a concrete fill disposed between the web of the I-beams and the adjacent end plates, said fill being extended upwardly in flush relation with the floor plates, substantially as described.
7. In a floor construction, the combination with a pair of I-beams of a shouldered block supported on each beam in parallelism with its web, a plurality of plates extending between the two beams and supported on the block shoulders carried thereby, the plates being so assembled as to provide upper and lower rows with interposed plates each interlocked with those adjacent whereby there results a plurality of transversely extending open spaces between the two beams, the interposed plates having openings through their bodies by which communica-
- tion between all of the said spaces is provided, substantially as described.
8. In a floor construction, the combination of a plurality of ceiling plates above which are a plurality of floor plates, there being also a plurality of web plates transmitting support from the ceiling to the floor plates, means for interlocking the several plates in unitary relation, there being open spaces at intervals between the adjacent edges of the several plates, wires extending from the body of each plate into the open spaces, and a fill of concrete disposed in the several open spaces and adapted to bury the wires to provide a tie between the several plates, there being suitable supports on which the ceiling plates are rested, substantially as described.
9. In a floor construction, the combination of a plurality of plates arranged edge to edge adapted to provide a floor, a plurality of web plates therebelow affording a support on which the floor plates are rested, means whereon the web plates are supported, means interlocking the web and floor plates and adapted to prevent displacement of either with respect to the other, and means connected with the web plates for supporting a ceiling therebelow, substantially as described.
10. In a floor construction, the combination with a pair of supports of a plurality of plates extended therebetween and supported thereby, each of the several plates being precast from concrete or the like, and having its opposite edges formed with a plurality of lugs, the several plates being assembled in double rows between which certain of the plates are interposed, the lugs on each plate being interlocked with those on the adjacent plates in the same row and with those on the proximate interposed plates so as to provide in effect a unitary structure, substantially as described.

WILLIAM E. RAMSEY.
